US00D775627S

(12) **United States Design Patent** (10) **Patent No.:** **US D775,627 S**
(45) **Date of Patent:** **** Jan. 3, 2017**

(54) **MOBILE DEVICE DOCK**

(71) Applicant: **Analogix Semiconductor, Inc.**, Santa Clara, CA (US)

(72) Inventors: **Kewei Yang**, Saratoga, CA (US); **André Bouwer**, San Jose, CA (US); **Marvin Su**, Palo Alto, CA (US); **Soumendra Mohanty**, San Jose, CA (US)

(73) Assignee: **Analogix Semiconductor, Inc.**, Santa Clara, CA (US)

(**) Term: **14 Years**

(21) Appl. No.: **29/525,468**

(22) Filed: **Apr. 29, 2015**

(57) **CLAIM**

The ornamental design for a mobile device dock, as shown and described.

DESCRIPTION

FIG. 1 is a top perspective view of a mobile device dock showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing the remainder of the mobile device dock are directed to environment. None of the broken lines form a part of the claimed design.

1 Claim, 5 Drawing Sheets
